UNITED STATES PATENT OFFICE.

JOSEPH PRONOVOOST, OF DETROIT, MICHIGAN.

RESILIENT WHEEL.

1,396,233.

Specification of Letters Patent.

Patented Nov. 8, 1921.

Application filed February 10, 1920. Serial No. 357,571.

To all whom it may concern:

Be it known that I, JOSEPH PRONOVOOST, a citizen of the United States, residing at Detroit, in the county of Wayne and State 5 of Michigan, have invented certain new and useful Improvements in Resilient Wheels; and I do hereby declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 The principal object of this invention is to improve upon the type of spring wheel, upon which I have obtained Letters Patent of the United States, #1220889 and #1220890, the improvement residing *inter alia* in constructing a wheel which presents improved riding qualities, which comprises a minimum number of parts and which is thoroughly practical from a manufacturing standpoint.

25 In the accompanying drawings, forming a part of this specification:

Figure 1 is a view in side elevation of a wheel constructed in accordance with my invention, one of the side plates or shields 30 being broken away to disclose the interior construction.

Fig. 2 is a view in end elevation, partly in section, of the wheel.

Fig. 3 is a detail view in side elevation of 35 the hub-member of the wheel.

Fig. 4 is a detail view in end elevation, partly in section, of said hub-member.

Fig. 5 is a detached detail view in side elevation of one of the two thrust plates of 40 the wheel.

Fig. 6 is a detached detail view in side elevation of two of the springs and related parts, the trunnions, or bearings, for the springs being shown in section.

45 Fig. 7 is a plan view of one of the spring frames before being bent up to shape.

Figs. 8 and 9 are detached detail views in side and end elevation respectively of said spring frame after being bent up to 50 shape.

Fig. 10 is a detached detail view in side elevation of one of the screw posts for the springs.

Fig. 11 is a plan view of a complementary spring frame before being bent up to shape. 55

Fig. 12 is a view in elevation of the cross bar forming a part of one of the units.

Fig. 13 is a view in elevation of the spring which operates in conjunction with the cross bar in each unit. 60

Referring now in detail to the drawings:

1 designates a rear hub-member, that is, a hub-member adapted for use on one of the rear wheels of a vehicle, having integral radial spokes 2, reinforced by a web 3, provided with apertured bosses 4, projecting on each side thereof, and through the apertures of which bolts 5 may pass to secure to said hub-member an annular plate 6, provided with a marginal flange 7, as shown in Fig. 2; nuts 5' being screwed on the threaded ends of said bolts. 65

The hub-member is preferably a malleable iron casting, provided at the outer ends of the spokes 2 with bosses 8 projecting on each side of the latter, and provided with aligned threaded apertures 9, as clearly shown in Fig. 4, for a purpose hereinafter appearing. The hub-portion is also provided with a rim 10. 75

80 Preferably a buffer 11, herein shown as of rubber, is disposed on the rim 10 and encircles the same. Concentrically disposed with reference to said hub-member 1, and surrounding the same as an outer wheel section made preferably as a metal casting and comprising an inner and an outer rim, 12 and 13 respectively, connected by spokes 14 radiating from said inner rim 12. The outer rim 13 is transversely apertured at spaced 85 intervals for the reception of bolts 15, carrying nuts 16, whereby metallic shields 17 and 18 are detachably fastened to said rim. The inner rim 12 is apertured at spaced intervals for the reception of pins or rods 19 which extend therethrough and project on 90 each side of the rim, as shown in Fig. 2. 95

Screwed into the threaded recesses 9 of the bosses 8, 8 are screw posts 20.

Disposed against each side of the hub-member 1 are thrust plates 21, 21, which, as shown in detail in Fig. 5, are substantially annular in shape and provided along their peripheries with scallops, or curved recesses 22, equidistantly spaced. Each plate 21 is 105 also provided with an annular series of aper-

tures 23, whereby securing means may pass therethrough to secure the plates to the hub-member 1.

Fig. 5 is a view of one of said plates on a reduced scale, it being apparent by inspection of Fig. 2 that said plates are of greater diameter than the hub-member 1, so as to project beyond the rim of the latter. As shown in dotted lines in Fig. 1 and in full lines in Fig. 2, the scallops 22 are disposed in alignment with the bolts or rods 19, whereby, in the operation of the wheel, said rods enter the recesses 22, which consequently act to take up the thrust.

15 A spring frame-member is shown in plan view in Fig. 7 before being bent up to shape, the said member being shown in Figs. 8 and 9 as being bent up to proper shape. As shown in Fig. 7, said spring member comprises a metallic strip provided intermediate its ends and on each side of the longitudinal center with longitudinally extending slots 22, 22, provided at one end with a curved enlargement 23. The strip is provided at 20 one end with a tongue 24, and is bifurcated at its other end as shown at 25. The metallic strip is bent centrally and transversely along the dotted line shown in Fig. 7, so as to present two side members 24, 24, as shown in Fig. 9, connected at one end by the curved bridge 25. The tongue 24 is bent into the bifurcated end 25 of the strip and is bent into bowed shape, as shown at 26, so as to conform to the contour of and to bear against the rod 19. The curved bridge 25 passes around the screw-member 20. In this position, side members 24, 24 of the spring frame are parallel, and the slots 22, 22 are also parallel.

40 A second spring member, shown in Fig. 11, comprises a metallic plate or strip provided intermediate its ends and on each side of the longitudinal center with two longitudinally extending slots 27, 27, provided each at one end with a curved enlargement 28. As shown in Fig. 6, the frame member is bent transversely at its longitudinal center so as to present the two side members 29, 29, connected at one end by the curved bridge 30, which passes around the bolt 19. The terminals of said side members 29, 29 are bent so as to provide outturned flanges 32, 32, which are engaged with a cross-bar 33, having a curved bearing portion 34, bearing 45 against the screw-member 20.

55 In the assembled position of the parts, as shown in Fig. 6, the side members 24, 24 and 29, 29 are disposed in parallel relationship and slide against each other. In this position of the parts, the slots 22, 22 and 27, 27 register. As shown in Fig. 2, a series of these complementary spring frame members is disposed on each side of the wheel and form supports for torsion springs 35, 35. Each 60 of said torsion springs is provided with a

coil, as shown, and the one terminal 36, 36 extends through the registering openings 22, 22 and 27, 27, and bears against one face of the cross-bar 33, as shown clearly in Fig. 6. The other terminal 37 of the spring is bent 70 at its end, as shown at 38, so as to bear against the curved portion 26 of one of the spring frame members.

It will be noted by reference to Fig. 1 that the spokes 2 of the hub-member 1 are disposed in staggered relation with the spokes 14 on the outer wheel section, and the frame members carrying the springs are disposed at inclinations to radial lines from the center of the wheel, so that said springs will readily 80 yield under pressure and successively be vibrated incident to the wheel rolling over the surface of the ground. It will also be noted, by referring to Fig. 1, that the spring frame members on one side of the wheel are 85 oppositely inclined to those on the opposite side of the wheel.

By the construction of the resilient wheel described, it will be noted that a torque is afforded, that is, the hub-member 1 will be 90 capable of a twisting action and that shocks coming from the motor or from a rapid throwing of the clutch will be absorbed.

Preferably the outer rim 13 on the outer wheel section is provided with a cushion 95 tire 39.

By the provision of a resilient wheel, made in accordance with my invention, it will be noted that a simple and efficient mechanism is afforded, in which the parts necessary to 100 accomplish the desired results are reduced to a minimum and are so arranged that the slightest vibration will be absorbed, so that a result equal to that obtained from the use of pneumatic tires is produced and whereby 105 a pneumatic tire may be dispensed with.

What I claim to be new is:

1. A resilient wheel comprising a hub portion having a rim with integral spoke sections, a boss at the end of each spoke section having a threaded recess, said spokes having bolt apertures, an outer rim section with bolt holes, bolts in said opposite sides of the wheel, oppositely disposed sliding frames engaging said bolts upon the hub 110 and rim section, and coiled springs interposed between and bearing against the opposite ends of said frames and tending to normally hold the rim and hub sections spaced.

2. A resilient wheel comprising a hub portion having a rim with integral spoke sections, a boss at the end of each spoke section having a threaded recess, said spokes having bolt apertures, an outer rim section with bolt holes, bolts in said holes and in said bosses, torsion springs arranged in pairs upon opposite sides of the wheel, oppositely disposed sliding frames engaging said bolts upon the hub and rim section, said springs 125

interposed between and bearing against the opposite sides of said frames and tending to normally hold the rim and hub sections spaced, and circular thrust plates fastened 5 to said hub section, and having recessed portions opposite the end of each spoke section of the hub.

3. A resilient wheel comprising a hub portion having a rim with integral spoke sections, with bosses having threaded recesses, at the outer end of each spoke, bolts engaging 10 said threaded apertures and having projecting ends, an outer rim section with

integral apertured spokes, bolts passing through apertures in the rim section, clevis-shaped spring frames engaging over the projecting ends of bolts upon the hub and rim sections and having sliding movements relative to each other and torsion springs carried by said frames and bearing against the 15 ends thereof, said springs reversely arranged upon opposite sides of the wheel.

In testimony whereof I hereunto affix my signature.

JOSEPH PRONO VOST.
